UNITED STATES PATENT OFFICE.

GEORGE W. GREENE, OF LOUISVILLE, KENTUCKY, ASSIGNOR TO TEN BROECK TYRE COMPANY, OF LOUISVILLE, KENTUCKY, A CORPORATION OF DELAWARE.

DESIGN FOR A TIRE.

48,374.

Specification for Design.

Patented Jan. 4, 1916.

Application filed July 10, 1915. Serial No. 39,201. Term of patent 7 years.

To all whom it may concern:

Be it known that I, GEORGE W. GREENE, a citizen of the United States, and a resident of Louisville, in the county of Jefferson and State of Kentucky, have invented a new, original, and ornamental Design for Tires, of which the following is a specification, reference being had to the accompanying drawing, forming part thereof, in which—

Figure 1, is a plan view of the tire forming the subject of my new, original and ornamental design, and Fig. 2, is a cross sectional view on the line II—II, Fig. 1.

The design for tire forming the subject

of my invention, comprises a rounded tread portion 10, and a circumferential rib 11 raised from the surface of such tread. Directly adjoining said rib are transverse ribs 13 substantially V-shaped in contour with their outer ends blending into the surface of the tread which ribs 13 form, with the circumferential rib 11, triangular recesses 14, and outer recesses 15.

I claim:

The ornamental design for a tire, substantially as shown and described.

GEORGE W. GREENE.
